CINEMATOGRAPHIC PROJECTION APPARATUS

Filed Oct. 4, 1927

UNITED STATES PATENT OFFICE

MAX ENGELMANN, OF LAUSA, GERMANY

CINEMATOGRAPHIC PROJECTION APPARATUS

Application filed October 4, 1927, Serial No. 223,977, and in Germany October 29, 1926.

The present invention relates to a cinematographic projection apparatus and especially to apparatus for cooling the film or the film track.

5 In the projection apparatus in which the picture band or film is illuminated by a very strong source of light, the band or film is so strongly heated that it would be ignited if the light were permitted to fall upon the film at rest. However, even when the apparatus is in operation the film becomes heated and in time becomes brittle. In addition to the film, the film track and the neighboring parts of the apparatus become strongly 15 heated.

In order to avoid these disadvantages air blasts have already been proposed which blow a stream of air under pressure against the film and the film track, and thus an excessive heating is prevented. In these proposed apparatuses the air from the compressor was led through tubes of flexible material from the exterior of the apparatus to the nozzles through which the air under 25 pressure was blown against the places to be cooled. These nozzles are positioned very near the film track or the film window, and it is known that these flexible air tubes which lead to the nozzles are very troublesome since 30 they prevent the operator from operating the film door easily and quickly. If rubber tubing is used for conducting the air under pressure, there also arises the great danger of easily damaging it in case it comes too near 35 the lamp house or other part of the apparatus.

According to the present invention a rigid tube is employed and it is placed in the interior of the completely inclosed mechanism. The conductor carrying the air under pressure enters the casing at a suitable place, while the tube proceeds to other places and leads into the blast nozzles. The tube may 40 branch off at different points in order to

supply several nozzles at the same time with air.

Figure 1 shows the apparatus with the lamp house and air compressor. Figure 2 shows the casing containing the driving mechanism with the back or outside wall removed. Figure 3 shows the said casing from the side and having the exterior wall partly broken away to exhibit the parts. Figure 4 is a view looking from the left side 55 of Figure 3 showing the position of the film in reference to the nozzles.

The compressed air is produced by the compressor 1 and is conducted to the apparatus by means of a tube conductor 2. The base 4 of the housing is provided with an opening 60 and carries a connecting sleeve 5. Connected with the sleeve 5 and within the casing is the tube 6 which leads from the sleeve 5 to a distributor 7 from which lead two more 65 tubes 8 and 9. These pass through the side wall 10 of the casing and end in nozzles 11 and 12, which are positioned near the film track 13 or near the film window 14.

The tubes 6, 8, 9, the distributor 7 and the 70 nozzles 11 and 12 are made of rigid material as described above and may be of metal such as brass or nickel or of a non-metallic and fireproof character such as asbestos in combination with a suitable binding agent, such 75 asbestos compositions being well known in the art. The tube 2 leading from the compressor may be of strong rubber hose but is also preferably of metal.

Having described my invention what I 80 claim is:

The combination with a cinematographic projection head and a film gate supported by said head and disposed outwardly thereof, of a vertically extending pipe arranged within 85 said head, a coupling arranged upon the upper end of said pipe, branch pipes each having one end connected to said coupling and its opposite end extended exteriorly of the head and projecting near the film gate on 90

the latter, a nozzle secured and connected to each of said projecting ends of the branch pipes extended exteriorly of the head, said nozzles being disposed adjacent the film gate 5 on each side thereof, and a main coupling arranged exteriorly of the head and connected to the lower end of the vertically extending pipe within the head, whereby an air supply conduit may be directly connected to said 10 coupling for the purpose specified.

In witness whereof I have hereunto set my hand.

MAX ENGELMANN.
